ATTY.

UNITED STATES PATENT OFFICE.

REGINA BRENDUM, OF WESTBY, WISCONSIN.

DESIGN FOR A FRAMED HARP.

46,659.

Specification for Design.

Patented Nov. 24, 1914.

Application filed October 8, 1913. Serial No. 794,172. Term of patent 3½ years.

To all whom it may concern:

Be it known that I, REGINA BRENDUM, a citizen of the United States, residing at Westby, in the county of Vernon and State of Wisconsin, have invented a new, original, and ornamental Design for Framed Harps, of which the following is a specification, reference being had to the corresponding drawing, forming part thereof.

The figure is a side elevation of a framed harp, showing my new design.

I claim:

The ornamental design for a framed harp, as shown.

REGINA BRENDUM.

Witnesses:

OLE L. LEUM,

PAUL STEENSON.
